RAILWAY CAR STRUCTURE

Harry M. Pflager, St. Louis, Mo., assignor to General Steel Castings Corporation, Granite City, Ill., a corporation of Delaware

Application December 23, 1933, Serial No. 703,806

58 Claims.

(Cl. 105—2)

My invention relates to a new and useful railway vehicle structure, and consists particularly in novel end construction of vehicles for high-speed trains.

5 Ordinary railway cars are coupled together at the center with couplers connected to the cars through springs, which allow limited motion between the cars. In order that the connected cars may go around curves, the end of each car, or 10 the so-called vestibule thereof, is tapered laterally in each direction from the center so that the cars when rounding sharp curves will not come in contact at the corners. When the cars are operated on straight track, this tapering of the 15 ends leaves a substantial space of about three feet between the adjacent corners of the cars, which space extends inwardly to a passageway enclosure at the center of the cars forming a pocket. The center enclosure is only high enough to allow headroom for passengers and 20 employees, leaving a space between the tops of the cars which also forms an air pocket.

The main object of the present invention is to do away with these spaces which offer great wind 25 resistance to cars when traveling at a high rate of speed.

A more detailed object is to produce a railway car or other vehicle so constructed that when two of the vehicles are coupled together, the entire 30 space between the adjacent ends of the vehicles is surrounded by a covering formed by shields or aprons substantially in line with the sides, roof and bottom of the car. This hood forms a substantially smooth and unbroken surface between the cars and thereby greatly reduces the 35 air resistance to the movement of the cars when running at high speeds.

The invention as herein illustrated is embodied 40 in a railway car having what is termed a movable end structure which is hinged at one side to a corner of the car body, stationary end structure and is movable at the other side so that it may travel inwardly and outwardly longitudinally of the car body.

45 The contour of this movable end structure at sides, top and bottom conforms substantially with the contour of the body so that when two of the cars are coupled together the side and roof portions of the abutting movable end structures are substantially flush with the sides and roofs of the cars, thus greatly reducing the wind resistance and resulting in the saving of power required to haul the cars at high speeds.

This arrangement is accomplished by providing 50 a strong buffer casting and corner post

structure at the end of the car for carrying the load of a movable end frame which is hinged to this buffer and corner post structure on one side of the car body, preferably the right hand side when facing outwardly. In addition to providing a strong and rigid support for the corner posts of the car and for the movable end frame, the buffer beam also provides a support and housing for the buffer mechanism, a support for the coupler or draw bar, and a support and housing for the draft gear. The movable end frame is made substantially to the contour of the outside of the car body and attached to the frame are aprons following the contour of the roof, side, and bottom of the car body, these aprons 15 moving inwardly and outwardly in recesses provided in the car body fixed end structure. The side apron is curved to a radius corresponding substantially to the width of the car.

20 While the movable end frame and its aprons are carried primarily by hinges mounted on the buffer casting and corner post structure on one side of the car body, a supplemental supporting member is provided on the other side of the car body which takes the form of a roller support 25 and stems inserted in the floor and roof supporting structure of the car body. Springs are mounted on the stems in order to position them outwardly to maintain the movable end frame in close contact with the opposing movable end 30 frame of the adjacent car regardless of whether the cars are on straight or curved track.

Several structures utilizing this general arrangement are shown in the accompanying drawings, in which—

35 Figure 1 is a top view of adjacent connected railway vehicles provided with the novel movable end structures.

Figure 2 is a side view of the same.

Figures 3, 5, 7 and 15 are horizontal sectional 40 views showing the same and taken substantially on the corresponding section lines of Figure 4.

Figure 4 is an end view of one of the cars showing the associated movable end structure in position.

45 Figure 6 is a detail vertical longitudinal section taken on the line 6—6 of Figure 4.

Figures 8, 9, 11 and 12 are partial vertical longitudinal sectional views taken on the corresponding section lines of Figure 3, Figures 9, 11, 50 and 12 showing portions of one car only.

Figures 10 and 19 are half vertical transverse sections taken on the corresponding section lines of Figure 3.

Figures 40 and 42 are detail vertical transverse sections taken on the corresponding section lines of Figure 34.

Figure 44 is a horizontal section showing still another modification and taken on the line 44-44 of Figure 45.

Figure 45 is a partial end view of the same.

Figures 46 and 47 are detail vertical longitudinal sectional views taken on the corresponding section lines of Figure 44.

Figure 48 is a detail vertical transverse section taken on the line 48-48 of Figure 44.

The novel end construction may be utilized with substantially any type of vehicle which is operated in trains, but is particularly advantageous when used in connection with railway passenger cars as shown in the drawings. In Figures 1 to 10 are shown adjacent connected passenger car bodies A and B of identical construction and mounting the movable end structures C and D, also identical. Each car body includes a curved roof 1, side walls 2 with window openings 3, and end walls, one of which is shown at 4, having corner posts 16 and 16a and intermediate end door posts 5 defining a relatively narrow center doorway equipped with a door 6 of any suitable type. The car underframe includes end sill 7, side sills 8, and center sills 9, and buffer beam 10, all of which may be formed, as shown, in an integral casting.

Projecting forwardly of the end sill 7 of each

car is a vestibule platform structure (see Figure 7) including the buffer beam or platform end frame 10 extending substantially from side to side of the underframe at an angle to the longitudinal center line thereof substantially varying from a perpendicular line thereto, and longitudinal sills 11 constituting extensions of the center sills 9 of the car and merging with the buffer housing 25. A horizontal web 11a cooperates with center sill extensions 11 to form a pocket 10 for resilient buffer mechanism, indicated at 28 in Figure 8.

The right hand side of the platform, shown as the lower part of Figure 7, is provided with a step opening 12 defined by the end sill 7, the outermost portion of buffer beam 10, the step 13 and riser 13a, and step support bracket 14. The step and riser and the step support bracket may be conveniently and advantageously formed integral with the end sill and buffer beam, as shown, in a manner to reinforce the platform adjacent the step opening.

Projecting above the buffer beam 10 is a vestibule end wall framing similarly disposed diagonally to the center line of the car (Figure 14). This framing includes substantial corner posts 15 and 16, a horizontal beam 17 at approximately the level of the member 18 forming the top of the body end doorway (Figure 8), a box section top member 19 corresponding in curvature with the top 1 of the car, and vertical struts 20. The corner post 15 is of substantial box section construction and tapers from bottom to top and is provided with hinge lugs 21, 22, 23 and 24 for the movable end structure. The tapering corner post provides substantial support for the associated movable end structures, to be described hereafter, and also provides better reinforcement for the platform adjacent the step opening.

Projecting forwardly from the center portion of the buffer beam 10 is the buffer housing 25 which may be of any suitable form but which is depressed on its top surface, as at 26, to provide space for the diaphragm bottom apron 27 (Figures 8 and 9). The buffering device shown includes single buffer stem 28a, relatively narrow mushroom head 28b, and buffering resistance 28. The ends of the center sills 9 may be provided with the usual draft lugs (not shown) for cooperation with draft mechanism, indicated in part at 29a in Figure 4, and the ends of the center sills are braced by transverse structure 29 to which may be secured a suitable draw bar carry iron.

The vestibule floor plate 30 is mounted on the end sill 7 and the diagonally disposed buffer beam 10 but projects outwardly beyond the buffer beam as shown in Figures 8 and 9. The outwardly projecting portion of flooring 30 is supported from the vestibule end framing above the buffer beam by means of a series of relatively light vertical channels 31 and 32 and angle post 33. Posts 31 and 32 are connected to vestibule end frame horizontal 17 by angle 31a and bar 34, respectively. Post 33 is braced from end frame top member 19 by angle bar 35. The space between posts 32 and 33 and the adjacent portion of the body end wall 4 beneath the level of member 17 may be conveniently inclosed by plates 36 and 37 and utilized as closet space, a door 38 being provided for entering the space from the vestibule. A roof plate 39 forms the top of the vestibule from side to side of the car. Plates 36, 37 and 39 are joined together and to

the supporting framing by corner angles 40, 41, 42, 43 and 44 (Figures 3, 9, 16 and 17).

On the outer side of this closet space is a relatively narrow space 45, located between the closet wall plate 37 and the car side sheet 2 and extending vertically from the buffer beam to the upper horizontal 17. This space forms a pocket for receiving the side apron 46 forming part of the movable end structure (Figures 3, 14 and 10 19). On the opposite side of the vestibule an upright end wall plate 36a is secured to the diagonal end frame adjacent the step opening.

At the left hand side of the vestibule, shown as the upper portion of Figure 7, a light frame or bracket projects outwardly from the buffer beam beneath floor plate 30 for mounting the lower edge of the car side sheet 2, this bracket including a longitudinal 47 forming a continuation of the side sill 8 and a transverse member 48 connecting the outer extremity of member 47 with the buffer housing 25. This bracket is arranged as at 49 for the attachment of a roller bearing 50 (Figure 13) for supporting the movable end structure in its telescoping movement in pocket 45. 25 A bracket 51 is secured to the wall 37 above roller 50 for supporting a second roller 52, the function and operation of these rollers being described in greater detail hereafter.

Movably supported on the adjacent ends of 30 the car bodies A and B are the separately formed, rigid, movable end structures C and D. Each of the movable end structures comprises a transversely disposed frame or body part extending from side to side and from top to bottom of the 35 car body, bottom and top aprons 27 and 69, and side apron 46. The frame is formed of vertical and horizontal members 55, 56, 57, 58, 59, 60 and 61 (Figure 4) and top member 62 forming substantially a continuation of corner posts 55 and 40 58. Members 59 and 60 are located at approximately the levels, respectively, of the buffer beam 10 and the vestibule end frame horizontal 17 forming part of the body stationary end structure. The bottom member 59 is centrally recessed at 51a (Figure 4) to clear the buffer mechanism. The top member 62 conforms in curvature with the top of the car body and is braced by vertical struts 63.

Each of the frame members of the movable end 50 structures described is flat on its outer surface and these cooperate to form face plate structure for engaging the corresponding portion of the 55 corresponding movable end structure on the adjacent car. Projecting transversely from one side and the top edge of the face plate frame and integral therewith is an apron supporting 60 frame including bottom horizontal 64, a curved inner edge beam 65 extending from member 64 to the top of opposite side post 55, intermediate vertical post 66, and rib-like horizontals 67 and 68. The side and top aprons 46 and 69 are formed by a separate curved triangular plate secured to this transverse framing. The bottom apron 27 is 65 triangular in plan and flat to conform with the vestibule or body end structure floor plate 30.

The movable end structure is hinged along its 70 left hand edge (Figure 4) to the tapering post 15 merging with the outermost corner of the vestibule platform adjacent the step opening. A direct supporting hinge connection is provided at the bottom as shown in Figure 6. This hinge comprises the perforated boss or lug 21 on the corner post 15, a superimposed supported lug 71 75 on the adjacent portion of the movable end struc-

ture, and a pin 72 closely fitting within and connecting the hinge lugs.

Flexible hinge connections are provided above the bottom hinge which permit relative vertical angular displacement between the body and movable end structures resulting from the passing of the car over a sharply changing incline. Each of the flexible connections is similar to that shown in Figure 5 in which a link 73 is pinned to the lugs 74 on the movable end structure corner post 55 and to the lugs 22 on the vestibule corner post 15. Pin 72 in the bottom connection is permitted slight play in the lower lug 70 to prevent injury to the hinge during relative tilting of the car body and movable end structure. 10 15

The movable end structure aprons 27, 46 and 69 are in lapping or telescoping relation, respectively, with the portions of the vestibule floor 30, the car side wall 2 and top 1 projecting beyond the slanting vestibule end wall, these portions 20 constituting, in effect, body end structure aprons cooperating with the movable end structure aprons.

As shown in Figures 3 and 14, the movable end structures C and D are pinned to diagonally 25 opposite corners of the adjacent vehicles A and B with the face plate portions abutting. Sufficient space is provided between the buffer beam 7, the bracket forming members 47 and 48, and the vestibule floor plate 30, in the pocket 45 and 30 beneath the curved roof member 1, to permit relative telescoping of the movable end structure aprons between the extreme positions indicated in Figure 14, in which the left hand structure C is compressed, and the right hand structure D is 35 correspondingly expanded.

In order to support the movable end structure at the side opposite the hinged connection, vertically spaced rollers 50 and 52 journaled in the car body end structure engage, respectively, 40 downwardly facing and upwardly facing surfaces of the bottom side apron frame member 64. These rollers serve as anti-friction bearings for the movable end structure and also resist vertical movement of the same relative to the associated body end structure. 45

A strip 75 of spring brass or similar material is secured to the end edges of the body side and top walls and overlaps the crevices between the same and the telescoping top and side aprons of the movable end structure. The strip 75 serves as a weather seal and preferably yieldingly engages the movable aprons. The bottom apron 27 and the overlapping vestibule floor 30 constitute 50 weather seal baffles at the bottom of the structure. 55

A lip 76 extends along the inner edge of the movable top apron 69 and forms a drainage channel for collecting moisture and cinders, which may sift past the sealing strip 75, and conduct 60 the same sidewardly (see Figures 16, 17 and 18). A lip 77 on the outer edge of the vestibule roof sheet 39 leads to an opening 77a at the side and serves a similar purpose. A plate 78 secured to the intermediate horizontal member 60 of the 65 movable end structure face plate frame extends immediately above the vestibule roof sheet and has a lip 79 on its inner edge for conducting foreign particles to the open sides 80 and 81 thereof. This member serves as a baffle to additionally protect the passageway through the center of the car end structure. 70

Each movable end structure is normally urged outwardly by lower and upper buffer devices 82 and 83 (Figures 3, 10, 12, 14, 15 and 18), which 75

are located between the hinge lugs 22, 23 and 24 and the center of the car where the relative movement between the body end and movable end structures is not as great as at the opposite side. 5 Each bottom buffer 82 (Figures 10, 12 and 14) comprises a stem 84 pivoted to perforated lugs 85 formed integral with the movable end structure bottom member 59 and extends through an opening 86 in the buffer beam 10 and an aligned opening 7 in the car end sill. A coiled spring 88 is compressed between the outer surface of the end sill and a collar 89 on the buffer stem. During relative movement of the body end and the movable end structures, the front end of the stem 84 is also moves a small amount in a horizontal transverse direction while the rear end pivots on its seat adjacent to the opening in the end sill 7. The opening 86 in the buffer beam provides clearance for stem 84 during its horizontal transverse movement. Excessive outward movement of the movable end structure is prevented by engagement of a nut 90 (Figure 3) on the extreme end of the buffer stem with the inner surface of the end sill. 15

25 Each upper buffer device 83 (Figures 15 and 18) comprises a stem 91 pivoted to perforated lugs 92 integral with horizontal 60 and a coiled spring 93 seated in housing 94 and engaging a collar 95 on the buffer stem. Housing 94 is formed integral with the vestibule end frame horizontal 17. A nut 96 serves to prevent excessive outward movement of the upper part of the movable end structure.

35 A vestibule doorway is provided in the car side adjacent the movable end structure hinges and opposite the side apron pocket 45. The step bracket 14 depends beneath this door opening and additional steps 97 are supported on this bracket and on the top step 13 formed integral 40 with the platform framing. Thus passengers enter the end of the car on one side only and may enter diagonally opposite corners of adjacent cars in a train.

45 The intermediate car body and vestibule end posts 5, 31 and 32 and the movable end structure center posts 56 and 57 of the adjacent cars cooperate to form a restricted passage between the cars. Curtains 98 connecting the longitudinally aligned vestibule end posts protect the sides of this 50 passageway from particles caught by the overlying webs 39, 69 and 78 (Figures 15 to 18) and directed sidewardly by the elevated ribs 77, 78 and 79. Face plate forming members 56, 57 and 60 of the movable end structures C and D may be positioned to cooperate with the face plates used 55 with the present restricted bellows-type diaphragms.

60 Mounted in the side door opening of each vestibule are doors E, each formed of a pair of vertical panels which may be folded upon each other in the open position (Figure 3) within the space above the tread of the bottom step. When closed, these doors are streamlined with the side wall of the car and the adjacent movable side apron. 65 Any suitable door may be provided.

66 Figures 20 to 24 illustrate a movable end structure F, in general similar to the structures C and D illustrated in the previous form. The face plate frame, however, is constructed of an integral cast body part including vertical posts 99, 100 and 101, bottom member 102 recessed at 103 to clear the buffer housing, intermediate horizontals 104, and a top horizontal member 105. Secured to member 105 is a separate top member 75 which may be conveniently formed integrally and

which is preferably of lighter metal or material, such as aluminum or fibre, and including attaching base 106, a curved top member 107, and short vertical struts 108, forming the upper portions of the face plate structure, and a web 109 curved in 5 transverse section and forming the top movable apron. Curved web 109 is reinforced by ribs 110 forming continuations of the web portions of T-section struts 108. Separate plates 111 and 112, which may be also of lighter metal or material, 10 secured to the side and bottom of the body portion form the movable side and bottom aprons. Apron 111 is reinforced by ribs 111a.

15 In Figures 25 to 28, the entire movable end structure G is formed as an integral casting including vertical posts 113, 114 and 115, bottom and intermediate horizontals 116, 117 and 118, curved top member 119, top apron 120 braced by ribs 121, side apron 122 and bottom apron 123.

Hinge lugs 124 and 125 and buffer lugs 126 are 20 also formed integral with the casting.

Figures 29 to 33 show a car body end construction H and hinged movable end structure J similar to the corresponding parts described in Figures 1 to 19, except that the buffer beam 127 is arranged 25 for mounting a wide double spring buffer device 128. The movable end structure bottom member 129 is recessed at 130 a sufficient width to clear the enlarged buffer device. It will be observed that the movable end structure is supported entirely 30 independently of the buffer mechanism and, accordingly, any suitable buffer device may be provided without reference to requirements for supporting this movable structure.

In Figure 33 is clearly shown the means for 35 supporting the swinging edge of the movable end structure upon the car platform, which means consists of rollers 131 and 132 engaging respectively upwardly facing and downwardly facing surfaces of the member 133 at the bottom of 40 framing mounting the side apron 134 and bottom apron 135.

In Figures 34 to 43, the side portions 136a and 136b of the bottom apron of movable end structure K extend beneath the buffer beam 138 and 45 the intermediate portion 136c of the apron extends above the buffer beam and immediately beneath the vestibule floor 139. In order to close the space between the adjacent edges of the portions 136a and 136c and portions 136b and 136c, 50 respectively, of the bottom apron, an auxiliary bellows-type diaphragm is provided consisting of folded strips 140 of flexible material. These strips extend between the bottom horizontal 141 of the movable end structure and the vertical fins 142 55 projecting laterally from the buffer housing. This divided construction of the bottom apron makes possible the extension of the platform framing including diagonal 143, longitudinal 144 and the end frame or buffer beam 138 a sufficient 60 distance outwardly from the car end sill 145 to support the entire vestibule floor and the substantial vestibule upright end framing members 146, 147 and 148. In this arrangement, the buffer beam 138 is permissibly less sharply inclined to 65 the center line of the car than in the previous forms.

Longitudinal 149 and transverse member 149a 70 form a light frame or bracket projecting outwardly from the end sill 145 beneath the platform framing for attachment of the car side sheet 150, this sheet being omitted in Figures 35 and 36 for clearer illustration. Space 151 is provided between the bracket and the overlying platform for telescopingly receiving portion 136a of the movable bot- 75

tom apron (Figures 36 and 37). Secured to this bracket and end sill 145 is a horizontal plate 152 carrying a weather seal strip 153 at its outer edge for yieldingly engaging the sections 136a and 136b of the bottom apron and serving as an additional weather seal. The provision of the substantial vestibule end members 146, 147 and 148 makes unnecessary the provision of additional light framing shown in Figures 1 to 19 for supporting the vestibule floor. Also the body end framing may be omitted except adjacent the stair opening, as at 154, and the car interior may thus be extended substantially continuously to the vestibule end walls 150a and 150b as shown. 15 The vestibule end framing may be conveniently formed integral with other parts of the car body end framing, suitable bracing members (not shown) being provided at the top.

The roller bearing 155 is secured to the substantial corner post 146 which extends into the pocket 158 for receiving the movable side apron 157, but does not interfere with the telescoping movement of this apron. In Figures 40 and 42 are shown the movable end structure bottom 25 buffer stem 159 passing through openings 160 in the buffer beams 138 and 161 in the end sill 145.

In Figures 44 to 48 the bottom apron 162 of the movable end structure L extends above the 30 buffer beam 163 from side to side as in the first forms described. Projecting horizontally above and outwardly beyond the buffer beam and the inner edge of apron 162 are a series of longitudinal beams 164 carried upon the platform and 35 upon which is mounted the vestibule floor 165. At the left hand side of the vestibule, the upper portion of Figure 44, where the diagonally disposed buffer beam 163 merges with the end sill 166, brackets 167 project inwardly from the end 40 sill to provide additional support for the two beams 164 beneath this portion of the flooring. The members 164 may be welded or riveted, or otherwise secured to the vestibule platform. The construction of the body and movable end structure in this form is otherwise the same as in 45 Figures 1 to 19, except that the angular braces 34 and 35 (see Figure 15) may be eliminated, the bracing beams 164 being adequate to support the vestibule floor.

50 The car stationary and movable structures described are of substantial construction calculated to withstand hard usage incident to high speed operation. The rigid movable aprons are obviously more durable and better adapted for streamline purposes than the bellows-type diaphragms now in general use. The diagonal disposition of the platform end frame or buffer beam as well as the vestibule end framing will tend to prevent telescoping of adjacent vehicles in case of abnormal impact, as under derailment or collision conditions, by causing the end of one vehicle to be displaced sidewardly relative to the other.

55 Preferably the intermediate vertical center posts of the movable end structure transverse framing are positioned to cooperate with the face plates at present utilized in connection with the narrow diaphragms, although obviously the full advantages of the construction are attained only where two cars with the novel cooperating end structures are connected together. The various overlapping aprons are preferably positioned together as closely as possible and if this proximity should give rise to undesirable scraping or clattering between the parts, suitable means may 60 be provided for deadening the objectionable

sounds such, for instance, as the formation of the diaphragm aprons of relatively soft material such as fibre or wood.

The invention may be advantageously utilized in connection with blind end cars, with articulated cars in which a single truck mounts the adjacent ends of two car bodies, locomotives, or any other streamlined railway vehicle having a load carrying body. The invention is not limited to the exact details of the embodiments described 10 but obviously many of the features may be modified to meet special conditions as will occur to those skilled in the art and the exclusive use of all such modifications as come within the scope of the appended claims is contemplated. 15

What is claimed is:

1. In combination in a railway train unit, adjacent vehicles having opposing movable end structures, the movable structure on each of said vehicles being hinged to a stationary member at 20 one side thereof, said structure extending transversely of the vehicle to the other side thereof and being there movable, about its hinge, longitudinally of the vehicle, the hinge part of one structure abutting the longitudinally movable part 25 of the other structure.

2. In combination, adjacent vehicles including connected body end structures, and movable end structure between the same and pivoted to diagonally opposite corners of said body end structures and having aprons in telescoping overlapping relation with the sides of said body end structures opposite the corners on which they are pivoted. 30

3. In combination, adjacent railway vehicles 35 including body side, top, and bottom walls, and body-connecting structure including relatively movable members each pivoted to one of said vehicles and having aprons in overlapping relation with the side, top and bottom walls of the 40 vehicle to which the structure is pivoted, the aprons on said members extending inside said walls and cooperating to close the space between the bodies of said vehicles to form a streamlined unit with said adjacent vehicles. 45

4. In combination, adjacent vehicle bodies and connecting structure therefor including relatively movable members hinged to diagonally opposite corners of the adjacent ends of said vehicles and aprons in lapping relation with the sides thereof, 50 said vehicles having diagonally opposite side doors adjacent said hinge corners.

5. In a railway vehicle, a body including stationary end structure, and movable end structure 55 on said body end structure and disposed to cooperate with end structure on an adjacent vehicle, the sides and top of said movable end structure forming extensions of the sides and top of said body and the sides and top of said movable end structure being positioned inside the sides and 60 top of said body end structure.

6. In connecting structure for railway vehicles, a frame, an apron member adjacent an outer edge of said frame, a baffle projecting from said frame and spaced from said apron member, and a drainage channel on said baffle. 65

7. In combination, vehicle body end structure comprising vestibule forming members including a top plate, and movable structure including an apron in telescoping relation with a part of said 70 body end structure above said top plate and a member extending immediately above said top plate and beneath said apron and including means for carrying off water and dust particles beneath said apron. 75

8. In combination, vehicle body end construction including end framing, a floor plate, and a bracket projecting from said framing, movable end structure for connecting the body to an adjacent vehicle and including an apron in lapping relation with said floor plate, and a weather seal member mounted on said bracket beneath said plate and apron.
9. Structure for connecting railway vehicle bodies and including a metal frame arranged to extend substantially from side to side of the vehicle bodies and integral lugs for attaching buffer stems for yieldingly thrusting the structure from one of the vehicle bodies.
10. Railway vehicle body end construction including a continuous pocket adjacent one side and the top thereof and extending substantially from top to bottom and from side to side of the same for receiving a relatively movable plate structure for connecting the vehicle body with an adjacent vehicle.
11. Railway vehicle body end structure including body top, side and bottom members forming a transverse upright frame extending diagonally of the longitudinal center line of the vehicle, and structure on said frame for mounting a movable end member for connecting adjacent vehicles and arranged for telescopingly receiving a part of said movable end member.
12. In a railway vehicle, side wall members, upright end structure extending diagonally from one of said side members to the other and serving to resist telescoping of the vehicle with an adjacent connected vehicle, there being a pocket adjacent one of said side wall members for receiving a movable end member for connecting adjacent vehicles.
13. Railway vehicle body end construction including hinge elements adjacent one side thereof for mounting movable structure for connecting the vehicle body with an adjacent vehicle, and a vertical pocket adjacent the other side thereof for telescopingly receiving a part of said movable structure.
14. Vehicle end construction including a corner post with hinge elements for mounting movable structure for connecting the vehicle body with an adjacent vehicle, body end framing extending diagonally therefrom to the opposite side of the vehicle, and a pocket in said opposite side for receiving a part of said movable structure.
15. Vehicle end structure including top bottom and side members, one of said side members having hinge elements for attachment of movable structure for connecting the vehicle body with an adjacent vehicle and the other side member being arranged for telescoping association with a part of said movable structure, and door framing elements formed as part of the structure immediately adjacent said hinge elements.
16. In a vehicle end structure, a rigid upright end frame member extending diagonally of the longitudinal center line of the vehicle, a movable upright end member having an inwardly extending apron on its lower portion, a floor above said apron, and members projecting outwardly from said end frame member for supporting said floor.
17. In a railway vehicle body end structure, a buffer beam extending diagonally of the longitudinal center line of the vehicle, a member projecting longitudinally outwardly from said beam at one side of the vehicle for mounting a body side sheet, and a pocket adjacent said beam for receiving a movable end member for connecting the vehicle with an adjacent vehicle.
18. In railway vehicle body end construction, a buffer beam extending across the vehicle, there being elements adjacent said beam for telescopingly receiving movable structure for connecting the vehicle body with an adjacent vehicle, and a bracket projecting outwardly from said beam for mounting body side plates and a weather seal for association with said movable structure.
19. Railway vehicle body end construction including an underframe end sill, platform framing projecting outwardly therefrom, and a bracket projecting from said sill beneath said framing for mounting a weather seal plate, the space between said framing and said bracket serving to telescopingly receive movable structure for connecting the vehicle body with an adjacent vehicle.
20. In vehicle body end construction, end framing including a buffer beam extending diagonally of the longitudinal center line of the vehicle, a floor plate projecting outwardly from said beam, and structure supporting said plate from said end framing above said plate.
21. In combination, railway vehicle body end framing and movable structure pivoted to said framing adjacent one side of the body and extending substantially to the opposite side thereof for connecting the vehicle body with an adjacent vehicle.
22. In combination, a vehicle body including rigid roof, floor and wall members, and movable structure for connecting the vehicle body with an adjacent vehicle and including rigid aprons mounted on said body disposed in slidable lapping relation and substantially flush with all of said body members said structure also including a face plate for abutting directly against a corresponding element of similar structure on an adjacent vehicle.
23. In combination, a car body including a rigid end wall, side and roof members projecting beyond said wall, and a movable structure independently secured to said body and including rigidly connected side and roof aprons disposed in lapping relation and substantially flush with the projecting portions of said body side and roof members terminating in face plate elements for abutting corresponding elements on an adjacent vehicle.
24. In combination, a car body including an end wall and side, floor and roof members projecting beyond said wall, and movable end structure including a frame hinged to one edge of said body and extending substantially to the other edges thereof, and aprons extending immediately adjacent to and in lapping relation with the projecting portions of said body members.
25. In combination, a vehicle body end structure and a movable end structure including an outer part for abutting against an adjacent vehicle, a hinged connection with said body end structure adjacent said outer part, and an apron spaced from said connection and in telescoping relation with said end structure.
26. In combination, vehicle body end structure including top, bottom and side members and end framing extending diagonally from side to side of the body, and movable end structure including a frame extending substantially from side to side and from top to bottom of the body and having face-plate-forming elements and aprons in lapping relation and substantially flush with said body top and side members.
27. In combination, vehicle body end structure

- including buffer housing and head elements, and a movable end structure for connecting the vehicle body with an adjacent vehicle and including framing extending transversely of the vehicle and supported independently of said elements on portions of said end structure spaced substantially therefrom.
28. In combination, vehicle body end construction including a buffer beam with a portion for receiving a buffer device, and a member extending transversely of the vehicle for connecting the vehicle body with an adjacent vehicle and including an apron in lapping relation with said beam and extending above said buffer receiving portion thereof and beneath the portions thereof at the sides of said buffer receiving portion.
29. In combination with adjacent vehicles, movable end structure on one vehicle including face plate elements located substantially inwardly from the sides of the vehicle body and movable end structure on the other vehicle including a frame extending substantially from side to side of the vehicle and having aprons flush with the top and a side and having intermediate vertical posts disposed to abut said face plate elements.
30. In a vehicle, body end construction including side members and end framing extending diagonally from one of said members to the other, and movable end structure for connecting the vehicle body with an adjacent vehicle and having an apron in lapping relation with one of said side members, there being a door opening in the other side member immediately adjacent said end framing.
31. In a railway vehicle, body end construction including a doorway at one side thereof and closet forming elements at the other side thereof, and movable end structure pivoted to said body end adjacent said doorway and extending adjacent said elements and across said body end for connecting the same with an adjacent vehicle.
32. In combination, vehicle body end structure, movable end structure for connecting the vehicle body with an adjacent vehicle, and a flexible hinge having vertical axes forming a pivotal connection between said body and said movable end structures and providing for relative linear displacement as well as relative angular movement of the associated portions of said structures.
33. In combination, vehicle body end construction, movable end structure for connecting the vehicle body with an adjacent vehicle and including a frame extending transversely of the vehicle, and a horizontal link pivoted to said end construction and to said frame and constituting a flexible pivotal connection therebetween, said pivotal connection having vertical axes.
34. In combination, vehicle body end structure, movable end structure for connecting the vehicle body with an adjacent vehicle and including a frame extending transversely of the vehicle, a simple pivoted hinge connection between the lower portions of said body and movable end structures, and a flexible hinge connection between the upper portions of said structures to accommodate relative tilting of said body and movable end structures as well as relative pivoting thereof in a horizontal plane.
35. In combination, vehicle body end structure, movable end structure for connecting the vehicle body with an adjacent vehicle and extending transversely of the vehicle and pivoted at one end to said body structure so that its opposite end portion moves substantially longitudinally, and an anti-friction bearing between adjacent parts of said body end structure and said opposite end of said movable end structure to facilitate longitudinal movement of the associated portion of said movable end structure.
36. In combination, vehicle body end structure, movable end structure for connecting the vehicle body with an adjacent vehicle and including a frame extending transversely of the vehicle and pivotally supported at one side on said body end structure, and a rolling bearing supporting the other end of said frame on said body end structure.
37. In combination, vehicle body end structure, movable end structure for connecting the vehicle body with an adjacent vehicle and extending transversely of the vehicle, and anti-friction bearings cooperating respectively with upwardly and downwardly facing bearing surfaces of one of said structures to facilitate relative movement of said surfaces longitudinally of the vehicle while preventing relative vertical movement thereof.
38. In combination in a vehicle, body end construction including end framing and side doorway elements, movable end structure for connecting the vehicle body with an adjacent vehicle and pivoted to said body adjacent said elements and including an apron in lapping sliding relation with the side of said body construction opposite said doorway elements, and a door associated with said elements, said movable structure and door forming elements of a streamlined exterior surface for the vehicle.
39. Movable end structure for connecting adjacent railway vehicle bodies and comprising a lower body part arranged to extend transversely of the vehicle and having elements for mounting the same upon the vehicle, and an upper body part formed of lighter material than said lower body part and including an apron and elements for attaching said second-mentioned part to said lower body part.
40. A movable end structure for connecting adjacent railway vehicle bodies and comprising an integral cast metal body part arranged to extend transversely of the vehicle and including hinge elements for attaching the same to the vehicle body, and a part attached to an edge of said cast body part and formed of material substantially lighter than the same, said second-mentioned part including an apron projecting transversely of said body part for telescoping association with the vehicle body end construction.
41. In combination, railway vehicle body and construction including a buffer beam and a floor plate above and projecting beyond the same, a movable end structure extending transversely of the vehicle for connecting the vehicle body with an adjacent vehicle and including a portion substantially paralleling said floor plate and spaced vertically therefrom and movable relative to said buffer beam, and an auxiliary upright diaphragm closing the space between said buffer beam, said floor plate, and said portion.
42. Vehicle body end construction including platform framing, a buffer beam, and a floor supporting element carried by said framing and projecting horizontally beyond and spaced above said beam, space being provided between said element and said beam for receiving part of a movable end structure for connecting the vehicle body with an adjacent vehicle.
43. In combination, vehicle body end construction including platform framing, horizontal members carried on said framing and projecting beyond the same, and flooring on said members.

- and a movable end structure for connecting the vehicle body with an adjacent vehicle and including framing extending transversely of the vehicle and an apron projecting between said members and a portion of said framing and in telescoping relation therewith. 5
44. In a railway vehicle, an underframe transverse end member, and a movable end member extending across the vehicle for connecting the vehicle with an adjacent vehicle and pivoted at one end of said underframe member. 10
45. In a railway vehicle, rigid body structure including an underframe transverse end member and a corner post, and a movable end member extending from side to side of the vehicle for engagement with an adjacent vehicle and hinged to said corner post. 15
46. In a railway vehicle, body end structure including an underframe transverse end member and a corner post rigid with one end of said end member, there being a recessed portion at the other end of said body end member, a movable end member extending transversely of the vehicle for engagement with an adjacent vehicle, 20 and rearwardly projecting apron structure at the top and one side of said movable end member, said movable end member being pivotally connected to said corner post and said recess accommodating substantially longitudinal movement of said apron relative to said member. 25
47. In a railway vehicle, body end structure including an underframe transverse end member and corner posts rigid with the ends of said end member, and a movable end member extending from side to side of the vehicle for engagement with an adjacent vehicle, one of said corner posts pivotally supporting said movable end member and said movable end member moving as a unit about said post. 30
48. In a railway vehicle, an underframe, a buffer beam rigidly supported by the end portion of said underframe, said buffer beam including a housing for supporting buffer mechanism, a support on said buffer beam for a coupler or draw bar, a support and housing on said buffer beam for draft gear, a corner post supported by said buffer beam, and a movable end member extending transversely of the vehicle and pivotally supported by an end portion of said buffer beam and by said corner post. 40
49. In a railway vehicle, a movable end member extending transversely of the vehicle from side to side and from top to bottom for engagement with an adjacent vehicle, and a transverse end member extending substantially from side to side of the car and forming a strong and rigid support for said movable end member, said movable end member being pivotally supported at one of the end portions of said transverse end member. 55
50. In a railway vehicle, a body, a transverse end member extending from side to side of said body and rigid therewith, a corner post rigidly supported at one of the end portions of said transverse member, said transverse end member and corner post forming a strong and rigid corner structure, and a movable end member extending transversely of said body from side to side and from top to bottom for engagement with an adjacent vehicle and pivotally carried by said corner structure. 60
51. A railway vehicle body end structure and a movable end member mounted thereon for connection with an adjacent vehicle, said member being in telescoping relation with at least one side and the top of the end portion of said body and the telescoping portions of said member extending inside of the end portions of said body. 5
52. In a railway vehicle, a body including stationary end structure, and movable end structure on said body end structure and including a face frame, said movable end structure being pivoted to said body end structure at a point in close proximity to the vertical plane of said face frame, and aprons projecting rearwardly from the top, bottom, and side portions of said face frame so as to overlap and be movable relative to the body end structure in close proximity to the outside thereof without binding therebetween. 10
53. A railway vehicle body end construction including hinge elements on one side thereof for mounting movable structure for engaging the end of an adjacent vehicle, and a pocket adjacent the top thereof for telescopically receiving a part of said movable structure. 15
54. In combination, railway vehicle body end structure, movable end structure for connecting the vehicle with an adjacent vehicle and pivotally supported at one side by said body end structure, and a rolling bearing between said structures at the other side and arranged to facilitate movement of said movable structure longitudinally of the vehicle. 20
55. A railway vehicle body-connecting structure including a frame with an outer face plate arranged to extend substantially from side to side and from top to bottom of the vehicle body, and a plate member extending transversely of said face plate and constituting an apron for closing the opening between adjacent car bodies, said frame including a portion extending laterally of said face plate across said plate member to mount and brace the latter. 25
56. In a railway vehicle, body side walls, a door frame in the end portion of one of said side walls, there being a longitudinally opening pocket formed in part by the corresponding portion of the opposite side wall, said pocket being constructed and arranged to receive the side apron of a movable structure for connecting the vehicle body with an adjacent vehicle body. 40
57. In combination, railway vehicle body end construction including a buffer beam and a buffer housing projecting therefrom, and movable end structure for connecting the vehicle body with an adjacent vehicle and including a bottom apron having a central portion located at the level of the top of said housing and having side portions located at a substantially lower level, and auxiliary upright diaphragms extending between the edges of the central and side portions 55 of said apron. 50
58. In combination, railway vehicle end construction including a bottom member, and movable structure for connecting said end construction with an adjacent vehicle and including framing extending substantially flush with the sides, top, and bottom of said body structure and a streamlined bottom apron extending beneath said bottom member for reducing resistance to air streams passing beneath said movable structure. 60

H. M. PFLAGER.
